HAIR WAVING PROTECTOR

Ralph M. Keele, San Francisco, Calif., assignor
to United States Appliance Corporation, San
Francisco, Calif., a corporation of California

Application September 30, 1932
Serial No. 635,470

3 Claims. (Cl. 132—36.1)

This invention relates generally to devices known as protectors, which are utilized together with other apparatus for the waving of human hair, particularly where heat is employed to render the wave relatively permanent.

It is an object of the invention to provide a protector which will afford a more adequate grip upon a strand of hair thus precluding the possibility of transmitting pull to the scalp, and which will also afford better protection against undue heating of the scalp by hot vapor.

A further object of the invention is to provide an article of manufacture, used in conjunction with other means to form a complete protector, and which will obviate difficulties inherent in prior protectors utilizing resilient gripping surfaces permanently secured to clamping bars.

Further objects of the invention will appear from the following description in which the preferred embodiments of my invention have been set forth in detail in conjunction with the accompanying drawings. The appended claims are to be accorded a range of equivalents consistent with the state of the prior art.

25 Figure 1 is a perspective view, illustrating the unit which I employ in conjunction with other clamping means to form a complete protector.

Fig. 2 is a side elevational view, in transverse cross section, showing the unit of Fig. 1 applied 30 to a strand of hair adjacent the scalp.

Fig. 3 is a plan view of the unit illustrated in Fig. 1, with clamping means associated therewith.

Fig. 4 is a side elevational view, illustrating the 35 clamping means applied to the unit of Figs. 1 and 2, in position for receiving a curler.

Fig. 5 illustrates the apparatus of Fig. 4, after the strand has been wound upon the curler, and the curler has been mounted upon the protector.

40 Fig. 6 is a cross sectional detail taken along the line 6—6 of Fig. 5.

Fig. 7 is a cross sectional detail illustrating suitable clutching means to be incorporated in conjunction with the curler.

45 Fig. 8 is a cross sectional detail taken along the line 8—8 of Fig. 7.

Fig. 9 is a plan view of a modified form of clamping means.

Fig. 10 is a side elevation of the clamp shown in 50 Fig. 9.

Fig. 11 is a cross sectional view similar to Fig. 6, but showing the clamp of Fig. 9.

The invention may be outlined briefly as comprising two units, one of which is made principally of resilient material such as soft vulcan-

ized rubber, and a clamping means adapted to be used in conjunction with the first unit and which serves to force certain resilient surfaces into tight gripping engagement with a strand of hair. Referring now to the drawing, the unit 60 which is formed principally of resilient material is indicated generally at 10. While its construction may vary somewhat, as illustrated it consists of a seal 11, which is provided with a longitudinal slot 12 to receive a strand of hair. In 65 other words this seal is formed of two elongated parallel portions 13, formed of resilient material, which have their end portions integrally joined together. For a purpose to be presently explained, resilient lips 14 extend laterally from 70 the sides and ends of the upper edge of the seal.

In addition to the seal 11, I further provide a skirt 15 which is likewise formed of resilient material. This skirt is integrally joined with the lower edge of seal 11, and extends laterally a substantial distance from the sides and ends of the seal. To afford better heat protection, the lower surface of skirt 15 is covered with a layer 16 of 75 soft felt or like material which is a relatively poor conductor of heat.

Since all of the parts of unit 10 are of resilient material such as soft vulcanized rubber, and are made integral, the unit as a whole can be readily flexed, and if desired the parts lying upon opposite sides of the slot 12 can be pulled apart 85 to provide an enlarged space thru which a hair strand can be drawn.

The resilient unit described above is adapted to be used in conjunction with some suitable mechanical clamping means, such as the means 90 17 illustrated in the drawings. In this instance clamping means 17 consists of a pair of bars 18 and 19, made of suitable material such as pressed sheet metal. One end of bar 19 is provided with an arm 20, which in turn has a pivotal connection 21 with bar 19. For forcing the free ends of the bars together, the other end of bar 18 is provided with a pivoted link 22. Pivotedly connected to link 22 there is a cam lock lever 23. Lock lever 23 is adapted to engage a hook-shaped 95 portion 24 provided upon one end of bar 19. Both of the bars 18 and 19 are provided with opposed flanges 26, for engaging the parallel portions 13 of the seal, between the lip 14 and the skirt 15, as shown in Fig. 6. Links 20 and 22 100 are also provided with upstanding slotted lugs or posts 27, to receive a suitable curler 28.

Curler 28 is preferably of the type, known in the art, which when positioned upon the protector can rotate only in one direction, to enable 116

- tensioning of the hair. Thus the squared pin 29 extending from one end of curler 28, and which engages a corresponding slot in one of posts 27, has suitable clutching means interposed between 5 it and the body of the curler. As shown in Figs. 7 and 8 this clutching means can be formed as follows:—Squared head 29 is formed upon one end of a pin 30, which in turn is disposed within a socket 31 formed in the end of the curler body.
10. A relatively flat strip of spring metal 32, is spiraled about pin 30, and has its one end disposed within a slot provided within the pin. With this arrangement pin 30, together with head 29, is free to turn with respect to the body of 15 the curler in one direction, but when relative turning movement in the opposite direction is attempted, spring strip 32 tends to expand, and its end 33 is jammed into engagement with the adjacent surface of the curler body.
20. The use of my invention in waving hair can be explained as follows:—After a strand of hair 36 has been segregated from a head of hair, a suitable hook-shaped tool 37 (Fig. 1), is thrust thru the slot 12, and engaged with the strand.
25. Upon retracting this tool, the strand is drawn thru the slot, this operation being facilitated by the fact that the side walls of the slot can be readily forced apart. Unit 10 is then moved to a position in close proximity to the scalp, as 30 shown in Fig. 2. After the strand has been properly distributed and arranged within the elongated slot, the clamping means 17 is then engaged with seal 11, in the manner illustrated in Fig. 3. Upon locking the free ends of bars 18 and 19 together, by links 22 and cam lock lever 23, the seal is forced into tight gripping engagement with the strand.

After the above operations are completed, the projecting portion of the hair strand is wound 40 upon the curler 28, this curler positioned upon posts 27, and then the curler given a further rotation to tension the wound hair. The apparatus is then ready for a steaming operation, to render the wave permanent, as is well-known in the art.

45. During the steaming operation, hot vapors evolved cannot pass down into contact with the scalp, due to the fact that elongated slot 12 is entirely closed, except of course for those opposed surfaces which engage the hair. Likewise vapors 50 cannot pass downwardly into contact with the scalp about the seal 11, because of the presence of skirt 15 which extends laterally from both the sides and ends of the seal. Skirt 15 also prevents contact between metal parts of the clamping means 17 and the scalp, so that even though 55 these metal parts may become heated during the steaming period, such heating cannot cause discomfort to the subject.

With respect to the effectiveness of the grip 60 afforded by the seal 11 upon the strand of hair, it may be noted from Fig. 6, that when the hair strand is tensioned by rotation of curlers 28, there is a tendency for the resilient material between the flanges 26, to be pulled upwardly to a 65 certain extent. However since the cross sectional area of this resilient material increases below the flanges 26, it is evident that such upward deflection of the resilient material causes a jamming or wedging action, so that in effect the hair

is more securely gripped. In other words there is an automatic wedging action tending to preclude any slippage of the hair with respect to the resilient seal.

In Figs. 9, 10 and 11, there is shown a modification of the clamping means, in which the clamping bars are provided with surfaces having relatively poor heat conductivity, for contacting with the resilient seal 11. Thus in this case the two clamping bars 41 and 42, are likewise formed of sheet metal, and have their outer longitudinal edges provided with oppositely bent tabs 43. At one end of the clamping means, the two bars 41 and 42 are pivotally connected by links 44. Likewise links 46 are pivotally connected to the free end of bar 41, and pivotally connected to links 46, there is a cam locking lever 47. Positioned upon the bars 41 and 42, are the longitudinal strips 48 which are made of some suitable material which is a relatively poor conductor of heat, such as wood, and which are longitudinally slotted to accommodate the clamping bars. It will be noted that the outer longitudinal edges of strips 48 are adapted to abut the tabs 43.

The clamping means last described is adapted 100 to be utilized in conjunction with the unit 10, in substantially the same manner as the clamping means 17. However as illustrated in Fig. 11, it will be noted that the metal parts of the clamping means are substantially entirely out of contact with the adjacent rubber surfaces, and therefore very little if any direct conduction of heat can take place between these parts.

I claim:

1. In a protector, a single piece of resilient 110 material formed to provide a longitudinally slotted seal adapted to engage opposite sides of a strand of hair and a skirt extended laterally from the sides and ends of the seal, and a layer of heat insulating material secured to the under 115 side of the skirt.

2. In a protector including a pair of clamping bars, a seal formed of resilient material, said seal including two elongated parallel portions adapted to engage opposite sides of a strand of 120 hair extending therethrough and having their ends integrally joined together, said elongated parallel portions being adapted to be releasably engaged by said clamping bars to force the same into tight gripping engagement with the strand of 125 hair, and a skirt of resilient material integrally joined to the seal, said skirt extending laterally from the sides and ends of said seal and being adapted to underlie said clamping bars.

3. In a protector, a pair of clamping bars, a 130 seal formed of resilient material adapted to be disposed between said bars, said seal including two elongated parallel portions adapted to engage opposite sides of a strand of hair extending therethrough and having their ends integrally 135 joined together, a skirt of resilient material integrally joined to the seal, said skirt normally underlying said clamping bars and extending laterally from the sides and ends of said seal, said seal together with said skirt being removable as 140 a unit with respect to said clamping bars, and means for forcing said clamping bars together upon the sides of said seal.

RALPH M. KEELE.
